J. KALMANOWITZ.

ADJUSTABLE WINDOW SCREEN.
APPLICATION FILED JAN. 7, 1918.

1,272,271.

Patented July 9, 1918.

JACOB KATMANOWITZ, INVENTOR
BY *Maurice Block*, ATTORNEY

UNITED STATES PATENT OFFICE.

JACOB KALMANOWITZ, OF BROOKLYN, NEW YORK.

ADJUSTABLE WINDOW-SCREEN.

1,272,271.

Specification of Letters Patent.

Patented July 9, 1918.

Application filed January 7, 1918. Serial No. 210,750.

To all whom it may concern:

Be it known that I, JACOB KALMANOWITZ, a citizen of the United States of America, residing at Brooklyn, Kings county, State 5 of New York, have invented certain new and useful Improvements in Adjustable Window-Screens, of which the following is a full, clear, and exact description.

This invention relates to improvements in 10 window screens, the object being to provide a window screen that is adjustable both vertically and laterally in order that the screen can be fitted to any window sash. My improved screen is arranged for disas- 15 semblage or separation into two parts each of which is a complete adjustable screen for half of a sash or window opening.

I will proceed to describe my invention in detail the novel features of which I will 20 point out in the appended claim, reference being had to the accompanying drawing wherein:—

Figure 1 is a face view of a window having my improved screen attached thereto;

25 Fig. 2 is an enlarged perspective view of a portion of some of the screen members;

Fig. 3 is a similar view of the right corner of the screen members to the right in Fig. 1;

Fig. 4 is an enlarged sectional detail view, 30 the section being taken on a line 4—4 in Fig. 1;

Fig. 5 is a vertical section, the section being taken on a line 5—5 of the upper subsection in Fig. 1; and

35 Fig. 6 is a perspective of the right corner, as viewed in Fig. 1, of the screen member to the left in Fig. 1.

My improved screen consists, in this instance, of four adjustably connected members, said members or screen subsections being connected one to the other in a manner to permit of the lateral adjustment of the sections and also to permit of a vertical adjustment. In other words, my improved 45 screen is assembled so that it can be made to fit window sashes of various widths and also telescoped or extended vertically.

My improved screen consists mainly of two sections A and B, one of which is im- 50 movable, the other movable. The immovable section is located preferably in the upper half of the window opening, the lower section being movable so as to cover or uncover the lower half of the window opening.

55 The upper screen section A consists of the

subsections 7 and 8 while the lower section B consists of the subsections 9 and 10. The subsections 7 and 8 are slidably connected to permit of a lateral adjustment and the subsections 9 and 10 are also slidably connected 60 for similar purpose. The sections A and B are connected together to permit of a vertical movement of said sections, one upon the other, although in practice the lower section B will be the movable section. 65

The upper section A, as has been stated, consists of the subsections 7 and 8. The subsection 7 consists of an angular corner member 11 turned over at its outer edge to form a vertical channel 12 to slidably receive the angular corner member 13 of the subsection B. The upper and lower horizontal members of the subsection 7 consist of channel members 14 and 15 (see Fig. 5), to slidably receive the upper and lower horizontal members 16 and 17 of the co-operating subsection 8 (see Fig. 1). The channels or horizontal members 14 and 15, of the subsection 7, are connected at their inner ends by a vertical channel member 18 (see Fig. 80 6), to receive a vertical member 19 (Fig. 6) of the subsection 9 of the lower screen section B, the vertical member 19 being the inner edge of the said subsection 9 of the lower section B. The inner vertical members 85 of the subsections 8 and 10 consist of strips 21 and 20 (Fig. 2) respectively; strip 21 connects the inner ends of the horizontal members 16 and 17 of the subsection 8 and the strip 20 connects the inner ends of the 90 horizontal members 22 and 23 of the subsection 10.

The outer ends of the horizontal members 16 and 17 of the upper section A, are connected by an angular strip 26 (Fig. 3) 95 having a channel 26^a to slidably receive the angular corner member 26^b which connects the outer ends of the horizontal members 24^a and 25^a of the subsection 10.

For the sake of clearness, each subsection 100 will be described. The subsection 7 consists of the channeled angular member 11, horizontal angular members 14 and 15 having the inner ends thereof connected by a vertical channel member 18. The subsection 105 9 consists of an angular corner member 13, which slidably engages the channel member 11 of the subsection 7, horizontal channel members 24 and 25 having their inner ends connected by a vertical strip 19 which 110

slidably engages the vertical channel member 18 of the subsection 7. The two subsections form a complete vertical adjustable screen which can be used independently 5 of the remaining subsections, which will now be described.

The subsection 8 consists of a channeled angular member 26, horizontal members 16 and 17, which are connected at their inner 10 ends by a vertical strip 21, the members 16 and 17 being arranged to slidably engage the horizontal channel members of the subsection 7. The subsection 10 consists of the angular corner member 26^a, which slidably 15 engages the channeled member 26 of the subsection 8, the horizontal members 24^a and 25^a and a vertical strip 20, which connects the inner ends of said horizontal members. The horizontal members 24^a and 25^a 20 of the subsection 10, slidably engage the horizontal channel members 24 and 25 of the subsection 9.

By this arrangement, I am able to provide a screen that is both laterally and vertically adjustable. The vertical corner members 11 and 26 are provided with ears 27 and 28 having openings for the passage of a screw in order that the upper section A can be secured to the upper half of the window 30 opening, hence in practice the upper section

A will be fixed and the lower section B movable or vertically adjustable.

As can be seen in Fig. 6, the channel members 14, 15, 24 and 25 of the subsections 7 and 9 are reversed relatively to each other, 35 hence the subsections 8 and 10 can be laterally adjusted. A latch 29 is provided, on the subsection 7, to retain the lower section in a raised position as shown in Fig. 1.

What I claim as my invention is:

A screen comprising an upper section and a lower section, each section being made up of two subsections, slidably connected, for extension, a vertical channel-member connecting the left-hand subsection of the upper screen section at its inner end, and a vertical strip carried at the inner end of the left-hand subsection of the lower screen section and slidably engaging the vertical channel member at the inner end of the said left-hand subsection of the upper screen section, whereby said screen sections will be interlocked.

Signed at New York city, N. Y., this 5 day of January, 1918.

JACOB KALMANOWITZ.
